UNITED STATES PATENT OFFICE.

MORTIMER B. MILLS AND HERBERT S. MILLS, OF CHICAGO, ILLINOIS.

MAIL-BOX, &c.

SPECIFICATION forming part of Letters Patent No. 775,630, dated November 22, 1904.

Application filed August 20, 1903. Serial No. 170,108. (No model.)

To all whom it may concern:

Be it known that we, MORTIMER B. MILLS and HERBERT S. MILLS, citizens of the United States, residing at Chicago, in the county of Cook and State of Illinois, have invented a new and useful Improvement in Mail-Boxes, &c., of which the following is a specification.

The primary object of our present invention is the provision of an improved mail-box equipped with numbering or printing mechanism whereby letters introduced may be numbered or have printed thereon the place and hour of deposit, or both, if desired.

The invention was primarily designed for use in combination with a coin-controlled lock controlling the operation of the machine and is so illustrated in the accompanying drawings for clearness of understanding, the claims in the present application being limited, however, to the construction of the mail-box without reference to the lock as being coin-controlled.

In the drawings, which show the preferred embodiment of the invention, Figure 1 represents an end view of our improved mail-box with one end plate removed, the closure device controlling the introduction of the mail being in its elevated or open position; Fig. 2, a similar view with the closure device in its depressed or closed position; Fig. 3, an enlarged broken sectional view looking at the inner side of the front of the casing, the section being taken as indicated at line 3 of Fig. 4; Fig. 4, a sectional view taken as indicated at line 4 of Fig. 3, the full lines indicating the position of the closure device in the closed condition and the dotted lines indicating the position thereof in the open condition; Fig. 5, a broken section taken as indicated at line 5 and showing a detail of the coin-controlled mechanism with the parts in one position; Fig. 6, a view similar to that of Fig. 5, showing the parts in another position; Fig. 7, a broken sectional view taken as indicated at line 7 of Fig. 3 and showing the locking means for the closure device which are connected with the coin-controlled mechanism; Fig. 8, a section taken as indicated at line 8 of Fig. 2 looking toward the rear of the box; Fig. 9, a broken section taken as in-

dicated at line 9 of Fig. 3 and showing the counting device; Fig. 10, a sectional view taken as indicated at line 10 of Fig. 3 and showing an indicator for indicating whether or not the box contains mail; Fig. 11, a plan view of a stationary plate constituting the upper wall of the letter-chute and the printing mechanism carried by said plate; Fig. 12, a section taken as indicated at line 12 of Fig. 11 and showing the printing mechanism in the depressed or printing position, and Fig. 13 a similar section showing the printing mechanism in the elevated position.

A description of the preferred construction is as follows: A represents a casing or mail-box having a front side A', a rear side A², and lateral sides A³ A⁴; A⁵, a lower door or closure device supported on vertical pivots *a* and provided at the lower free corner with a lug *a'*, said door serving as a closure whereat the mail may be removed; A⁶, a top for the mail-box connected with the rear upper portion of the box by pivots *a*² and constituting a movable upper closure device whereat the letters may be introduced; A⁷, an opening or cut-away portion at the upper portion of the front of the box, affording an opening whereat mail may be introduced when the cover is in its elevated position; B, a horizontally-disposed letter-chute comprising a fixed upper plate B' and swinging angular members B² B³, supported on pivots *b*; C, a rock-shaft extending parallel with the front of the casing and journaled near one end in a bearing *c*, rising from the plate B', and journaled at the other end in a suitable bearing (not shown) with which the end plate A⁴ of the casing is provided; C', a cam-arm fixed to the shaft C and serving to lift the cover or upper closure device; C², an arm fixed at its upper end to the shaft C and equipped at its lower end with a pawl C³, engaging the curved rack or toothed segment C⁴, which is fixed to the inner surface of the casing - plate A⁴; C⁵, a handle through the medium of which the shaft C is actuated; D, a printing mechanism frame connected at its rear end by means of a pivot *d* with the rear end of the fixed plate B' of the letter-chute and having an arm *d'*, connected by a spring *d*² with a collar *d*³ on

the rock-shaft C; D', a printing-wheel having a shaft D² suitably journaled in the front end of the frame D and equipped at one end with a ratchet-wheel D³; D⁴, a forwardly and upwardly inclined arm connected rigidly with the frame D and serving as a medium for raising the printing mechanism, said arm D⁴ having a laterally-projecting stud d⁴; D⁵, a lug with which the lower front portion of the member A⁶ is equipped on its inner surface and which serves during the elevation of the member A⁶ to raise the printing mechanism through the medium of the arm D⁴; D⁶, a locking-pawl for the printing-frame, carried by a pivot d⁵, supported by a lug d⁶ on the upper surface of the front portion of the plate B', said pawl having a locking-shoulder d⁷ for engaging the stud d⁴ and a forwardly-projecting short arm d⁸, with which engages a laterally-projecting stud d⁹, carried by the lug D⁵ and serving to trip the pawl D⁶ when the cover A⁶ is depressed; D⁷, an arm connected with the frame D by means of a pivot d¹⁰ and equipped at its front portion with an inking device D⁸, having at its lower portion a lateral projection D⁹, from which depends a tooth d¹¹, riding upon the ratchet-wheel D³; D¹⁰, a spring connecting the arm D⁷ to the frame D; D¹¹, a pawl pivotally supported on a standard d¹², rising from the plate B', said pawl bearing a laterally-projecting stud d¹³, which serves during the elevation of the printing-frame to engage the ratchet-wheel D³ and rotate the printing-wheel; E, a shield or guard arranged beneath the front portion of the plate B' and connected by pivots e with the front end of said plate, said device E being provided at its rear end with a supporting-arm e', having a lateral projection e'', which engages the upper surface of the plate B'; F, an enlargement with which the front portion of the cover A⁶ is equipped on its outer surface and which serves as a housing for a counting device F' and an indicator F²; G, coin-controlled mechanism controlling the closure device A⁶ and comprising a coin-actuated member G' having a shaft G², journaled in suitable bearings f, and a coin-actuating cylindrical hood G³, having end portions journaled on the shaft G²; G⁴, an actuating-arm formed integrally with the hood G³; G⁵, a link connecting the extremity of the arm G⁴ with a lug f' on the inner surface of the front portion of the cover A⁶; G⁶, a locking-dog supported on a pivot g, projecting inwardly from the side A⁴ of the casing, said device having a hook or locking-shoulder g' at its upper extremity and a short arm g² at its lower portion connected by a spring g³ with the plate A⁴; G⁷, a triangular member fixed on the shaft G² and serving in the initial movement of the cover A⁶ to release the locking device G⁶; H, a coin-slot-closing plate slidably connected with the cover A⁶; I, a link connected with an arm I' of the indicator

F², such link being provided at its lower end with a projection h for engaging the lugs a' on the door A⁵ and a rearwardly-projecting arm h', which serves as a weight, tending to throw the lower end of the link I forwardly; I², a guide for the lower portion of the link I; J, a rock-lever supported on a pivot k, projecting forwardly from the rear plate of the casing; J', a link connected with one arm of the lever J and with a fixed arm J², with which the member B³ of the letter-chute is provided; J³, a link connected with the other end of the lever J and with the member B² of the letter-chute; J⁴, a link connected by a pivot k' with the lever J and provided with a trip-arm J⁵; J⁶, a link supported on a pivot k², projecting from the plate A² and having its upper end connected by a pivot k³ with the link J⁴ near the central portion thereof; J⁷, an arm connected at its front end by a pivot k⁴ with a lug k⁵ on the casing-front; J⁸, a link connecting the arm J⁷ with a lug k⁶, with which the cover A⁶ is provided on its inner surface, and K a box for maintaining the letters in the order of their introduction.

The casing or receptacle may be of any suitable construction. We have shown the end A³ removable, a portion of said end being shown by broken lines in Fig. 2. The upper end of the member A³ is provided with a slot l, (shown in dotted lines in Fig. 2,) which permits the casing end to be put into position with relation to the shaft C, which projects beyond the end and bears the handle C⁵. The cover or letter-chute-closure device A⁶ is of the curved form illustrated, having end flanges l', which embrace the outer upper margins of the ends of the casing. The member A⁶ is provided at its front lower inner margin with a lug l'', which affords a locking-shoulder for engagement with the shoulder g' of the locking device G⁶. The stationary front of the casing has its upper edge bent inwardly at the opening A⁷ and is provided thereat with a strengthening-rib l³. To the inner surface of the door A⁵ is connected a coin-receptacle m, which may be provided with any suitable means for preventing removal of the coins therefrom by unauthorized persons and which may be removably connected with the door in any suitable manner. The casing-front is provided with a short chute-section m', which receives the coin from the coin-actuated member G' and delivers it to the receptacle m.

The letter-chute B is directly in the rear of the opening A⁷ in the casing-front, so that when the closure device A⁶ is raised a letter may be inserted freely. Each of the members B² B³ comprises a bottom section n and a side section n'. The side sections n' are equipped with lugs n², which are supported on the pivots b. From Fig. 8 it will be understood that when the sections B² B³ are

dropped from the position indicated in dotted lines to the position indicated in full lines the cross-section of the letter-chute will be increased, so that the letters will fall freely into the box, even though they are forced into the passage of the letter-chute in the folded position thereof under a considerable pressure. The upper plate B' of the letter-chute is firmly secured to the casing at its rear end by a lug 10 n³ and at its front end by lugs n⁴. It is provided with an opening p, permitting the printing-frame and printing-wheel to spring to the position indicated in Fig. 12. The support e of the guard E passes through this slot or 15 opening and hooks over the upper surface of the plate B'. The cover A⁶ is equipped on its inner surface with a cam q, having inclined surfaces q' q². The guard E is provided with a perforation r, which serves to permit the 20 printing-wheel to extend through the guard. The enlargement F is provided with slots s s', through which the counting device F' and the indicator F² may be viewed. The counting device is provided with an arm s², which drops 25 by gravity when the cover A⁶ is raised and is elevated by means of a lug s³ on the plate B' when the cover A⁶ is depressed. The counting device is of any ordinary construction and is actuated when the cover A⁶ is depressed. 30 The arm I' is rigidly connected with the rotary indicator F² and bears normally upon the lower end of a slot s⁴ in the cover A⁶. When the cover is elevated, the link I is raised through the medium of the arm I' and is permitted to swing forwardly, so that its lower 35 end rests upon the lug a' of the door A⁵. When the cover A⁶ is depressed, the arm I' is swung to the position indicated in dotted lines in Fig. 10. In one position of the arm I' the surface 40 s⁵ of the color of the casing is exposed at the slot s', and in the other position of the arm the surface s⁶ of a different color calculated to attract attention is exposed at said slot. Thus if the closure device A⁶ has been actuated this 45 fact will be indicated by the surface s⁶ being shown at slot s'.

The member G' is shown provided with three non-radial coin-recesses t, which correspond with the three sides of the triangle G⁷. 50 In any position of rest of the member G', therefore, a coin-recess is presented to a slot t', with which the casing-front is provided. The cover A⁶ is provided with a slot t², which registers with the slot t' when the cover is in its depressed position. The member H rests normally upon the upper edge of the casing-front A', with its lower edge forming the upper wall 55 of the slot t'. When the cover is raised, the slot t' is moved upwardly with relation to the slot t' (the member H remaining stationary) and the insertion-passage is closed.

The pawl C⁸ is supported on a pivot v, projecting laterally from the lower end of the arm C⁹, and the upper end of the pawl is connected by a spring v' with a stud v² on said

arm. The length of the portion of the pawl which is beneath the pivot v is a little greater than the distance between the teeth of the segment C⁴ and the pivot, so that the pawl will lock the arm C⁹ against retrograde movement 70 regardless of direction of movement when the pawl is in engagement with the teeth of the rack; but the movement of the arm C⁹ may be freely reversed after the arm has completed its traverse.

The indicating device D⁸ comprises a cylinder equipped at its lower end with a pad w, the cylinder being filled with a semifluid ink which will be absorbed by the pad and applied to the printing-wheel. The cover A⁶ is 80 equipped at one of its flanges l' with a cam x, and the handle C⁵ is provided with a laterally-projecting stud x', which works over said cam. The cam is of suitable shape to permit the cover to rise when the handle is turned in 85 the proper direction and to prevent the cover from being raised independently of the operation of the handle.

From the foregoing detailed description the operation will be readily understood. A 90 person wishing to send a letter by special delivery inserts the proper coin, usually a dime, at the slot t', Fig. 5. This couples the members G G' of the coin-controlled mechanism together. As shown in Figs. 4 and 7, there 95 is in the position of rest a space between the locking-lug l' of the cover A⁶ and the locking-shoulder g' of the device G⁶. This permits initial movement of the cover. After inserting a dime the operator grasps the handle C⁵ 100 and draws it forwardly from the position shown in Fig. 2. This action serves to move the cover A⁶ initially, turn the member G³ through the medium of the link G⁵, and thereby actuate the member G' through the medium of the coin. This causes the triangle or star-wheel G⁷ to rotate, thereby unlocking the device G⁶ and permitting the cover to rise the full distance. As the shaft C rotates the arm C⁹ is carried around, locking the shaft 110 against retraction. As the cover rises it lifts the lever J⁷ through the medium of the link J⁸, bringing the free end of the lever J⁷ up beneath the adjacent end of the lever J, thereby rocking the lever J to the position indicated by dotted lines in Fig. 8. This causes the sections B² B³ of the letter-chute to be 115 swung upwardly to the closed position. Also as the cover is raised it lifts the printing mechanism through the medium of the lug D⁴ and the printing-frame extension D⁴ till the pawl D⁶ engages the stud d¹ on the printing-frame and locks the latter in its elevated position. While the printing-frame is being raised, the stud d¹³ of the pawl D¹¹ (which is 120 carried by stationary supports) engages the ratchet-wheel D⁸ and causes it to rotate. As the tooth of the ratchet-wheel passes beneath the tooth d¹¹ of the extension D⁹ of the inking device the inking device is swung up- 125 130

wardly on the pivot d^10 , permitting the printing-wheel to rotate freely. Furthermore, as the cover A^6 is raised it lifts the link I through the medium of the arm I' of the indicator, and the weight h' at the lower end of the link causes the link to swing forwardly and rest upon the lug a' of the door A^5 . By the time the cover has reached its highest position the cam-arm C' has passed the down-turned apex of the cam q , thereby holding the cover securely in its elevated position, as indicated by dotted lines in Fig. 4. With the cover in its elevated position the letter may be inserted freely through the opening A^7 into the letter-chute, where it will rest upon the bottom of the letter-chute composed of the portions n of the sections $B^2 B^3$. In the closed position of the bottom sections of the letter-chute the device E rests upon the bottom of the letter-chute. Accordingly when a letter is inserted, it is frictionally engaged by the device E , thereby preventing it from passing beyond the printing-wheel. After the letter or package has been inserted the lever C^5 is thrown from the position indicated in Fig. 1 to the position indicated in Fig. 2, thereby dropping the cover A^6 to its closed position. As the cover drops the stud d^9 of the lug D^6 strikes the short arm of the pawl D^6 and unlocks the printing-frame, thereby permitting the printing-wheel to fall upon the letter. This tripping action at the printing mechanism occurs soon after the cover starts to move downwardly and before the free end of the lever J^7 can reach the position shown by the full lines in Fig. 8. When the free end of the lever J^7 does reach the position shown by the full lines in Fig. 8, it drops the toggle-joint of the links $J^4 J^6$ through the medium of the extension J^5 , thereby permitting the bottom sections of the letter-chute to swing downwardly and drop the letter into the mail-box. While the cover is being lowered the lug s^3 engages the actuating-arm s^2 of the counting device, as illustrated in Fig. 9, thereby causing the operation to be registered. It should be stated that after the triangular member G^7 has acted upon the device G^6 to cause the cover to be released the device G^6 reacts upon the member G^7 to cause the member G' to move with relation to the member G^3 , thereby releasing the pressure from the coin and permitting it to fall into the coin-receptacle. The link I after being raised to the elevated position remains in that position until the door A^5 is opened to remove the mail, when the link is again freed and permitted to drop. Thus the indicator remains in a position to show when a letter has been inserted until the mail-box is opened to remove the mail.

It will be readily understood that many changes in details of construction within the spirit of our invention may be made. Hence no undue limitation should be understood from the foregoing detailed description, the same

having been given for clearness of understanding only.

What we regard as new, and desire to secure by Letters Patent, is—

1. In a mail-box, the combination of a suitable receptacle, a closure device, and a letter-chute guarded by said closure device and having a movable wall lying in a given plane during the insertion of a letter and moving bodily to enlarge the passage after the closure device has been substantially closed, and a suitable printing device coacting with said letter-chute. 75

2. In a mail-box, the combination of a suitable receptacle, a closure device, a letter-chute 80 having a movable wall lying in a given plane during the insertion of a letter and moving bodily to enlarge the passage after the closure device has been substantially closed, a suitable printing device located adjacent to said 85 letter-chute, manual actuating means, and operative connections between said actuating means and the printing device and closure device.

3. The combination with a suitable receptacle, of a rearwardly-opening top constituting a closure device, means for limiting the movement of said top, actuating means for said top, printing mechanism located beneath and actuated through the medium of said top, 95 and means for holding a letter during the printing operation. 90

4. The combination of a suitable receptacle, a letter-chute therein having a normally depressed lower wall, a movable top for said receptacle, means connected with said top for raising the lower wall of said letter-chute to the closed position, and means for actuating said top. 100

5. The combination of a suitable receptacle, 105 a horizontally-disposed letter-chute therein having a fixed upper wall and a movable normally depressed lower wall, printing mechanism disposed at the upper side of said letter-chute, a closure device, means for actuating the closure device and limiting the movement thereof, and means connected with the closure device and serving to raise the movable wall of said letter-chute, when the closure device is opened. 110

6. The combination of a suitable receptacle, a horizontally-disposed letter-chute therein having a fixed upper wall and a movable lower wall, printing mechanism disposed at the upper side of said letter-chute, a closure device, 120 means for actuating the closure device and limiting the movement thereof, means carried by the closure device for actuating the printing mechanism, and means connected with the closure device and serving to operate the movable wall of said letter-chute. 115

7. The combination of a suitable receptacle, a substantially horizontally disposed letter-chute therein having a fixed upper wall and movable side and bottom walls, printing mech- 130

anism disposed above said letter-chute, a movable closure device, means for actuating said closure device and limiting the movement thereof, means for actuating the printing mechanism, and means connected with said closure device and actuating said movable walls of said letter-chute.

8. The combination of a suitable receptacle provided at its front portion with a letter-insertion passage, a substantially horizontally disposed letter-chute within said receptacle having a swinging lower wall, a top pivotally connected with the rear portion of said receptacle and having its front portion serving as a means for closing said insertion-opening, means for actuating said top and limiting the movement thereof, and actuating means for the movable wall of the letter-chute connected with and actuated by said top.

20 9. The combination of a suitable receptacle, a substantially horizontally disposed letter-chute therein, printing mechanism disposed above said letter-chute and having a frame pivotally connected near the rear portion of the letter-chute, a top constituting a closure device for the letter-chute and pivotally connected at its rear portion near the rear portion of said letter-chute, means carried by said top for raising said printing mechanism, 30 and means for actuating said top and limiting the movement thereof.

10. The combination of a suitable receptacle, a swinging top therefor constituting a closure device, a rock-shaft extending transversely of the receptacle, cam connections between said rock-shaft and top, and an actuating-handle for said rock-shaft.

35 11. The combination of a suitable receptacle, a substantially horizontally disposed letter-chute therein, a printing device having a frame pivotally connected near the rear portion of said letter-chute, a swinging top constituting a closure device, a pawl for locking the printing device in the elevated position, 45 means carried by said top for elevating the printing device when the top is raised and dropping the printing device when the top is lowered, and means for actuating said top and limiting the movement thereof.

50 12. The combination of a receptacle, letter-chute, a printing device having a swinging frame, an inking device carried by an arm swinging upon said frame, a swinging top constituting a closure device, means carried by said top for actuating the frame of the printing device, a ratchet-wheel connected with the printing-wheel of the printing device, a pawl carried by a stationary support and acting upon said ratchet-wheel, means 60 connected with said inking device and bearing upon said ratchet-wheel, whereby the inking device is moved with relation to the printing-wheel, and means for actuating said top and limiting the movement thereof.

65 13. The combination of a receptacle, a hori-

zontal letter-chute having a stationary upper wall, a printing device having a frame pivotally connected with the rear portion of said letter-chute and having an upwardly-projecting arm, a suitably-sustained spring connected with said upwardly-turned arm and serving to depress the printing device, a closure device for said receptacle, and means for actuating said closure device and limiting the movement thereof.

70 14. The combination of a suitable receptacle, a swinging top constituting a closure device, a rock-shaft journaled in stationary supports, a cam connected with said rock-shaft within the receptacle serving to raise said top, a cam connected with the outer surface of said top, and an operating-handle connected with said rock-shaft and provided with means engaging said last-named cam on its upper surface.

75 15. The combination of a receptacle, a substantially horizontally disposed letter-chute having swinging sections constituting the lower and side walls of the letter-chute, a rock-lever connected with said sections, links forming a toggle-joint connected with said rock-lever, a suitably-actuated closure device having limited movement to permit insertion of mail, and actuating means connected with said closure device and serving to operate the swinging sections of said letter-chute.

80 16. The combination of a receptacle, a letter-chute, having a stationary wall and movable sections constituting the opposite wall and the side walls, said sections being pivoted outside their portions constituting the side walls, a suitably-actuated closure device having limited movement to permit insertion of mail, and actuating means for said swinging sections actuated with said closure device.

85 17. In means of the character described, the combination of a receptacle, a letter-chute having two normally depressed sections, a suitably-actuated closure device having limited movement to admit mail, and common actuating means for the closure device and normally depressed letter-chute sections, for the purpose set forth.

90 18. The combination of a suitable receptacle, a printing device, means for holding a letter during the printing operation, a swinging top constituting a closure device for the letter-chute, a counting device carried by said top and provided with a suitable actuating-arm, means connected with said receptacle for operating said counting device, and means for actuating said top and limiting the movement thereof.

95 19. The combination of a receptacle, a letter-chute having swinging lower sections, a swinging top constituting a closure device, an arm J' serving to actuate said swinging sections, and a link connecting said arm with said swinging top, for the purpose set forth.

100 20. In means of the character described, the combination of a receptacle, a swinging top

130

75

constituting a closure device, a letter-chute, means including a rock-shaft for actuating said top and limiting the movements thereof, and means including an arm fixed to said rock-shaft for insuring complete movements of said top, for the purpose set forth.

21. In means of the character described, the combination of a receptacle equipped with a toothed sector, a letter-chute, a swinging top 10 constituting a closure device, a rock - shaft equipped with an arm provided with a pawl engaging said sector, and cam connection between said rock-shaft and top, for the purpose set forth.

22. In means of the character described, the combination of a receptacle, a horizontally-disposed letter-chute having a perforated stationary upper wall and swinging sections constituting the lower and side walls, a guard 20 projecting into said letter - chute, printing mechanism operating through the upper wall of the letter - chute, a closure device, and means for actuating said closure device and limiting the movement thereof.

23. In means of the character described, the combination of a receptacle, a letter-chute, a closure device therefor, a rotary indicator carried by said closure device and provided with an actuating-arm, a link depending from 30 said arm, a door through which mail may be removed equipped with a lug serving to hold

said link in the elevated position, and means for actuating said closure device and limiting the movements thereof.

24. In means of the character described, the combination of a suitable receptacle, a substantially horizontally disposed letter - chute therein having swinging lower sections, actuating means for said sections including a toggle-joint equipped with a trip-arm, a suitably-actuated closure device for the receptacle having limited movement to permit insertion of mail, and a lever connected with and actuated by said closure device and serving to elevate said lower letter-chute sections 40 when moved in one direction and to trip said toggle-joint when moved in the other direction, for the purpose set forth.

25. A mail-box comprising a suitable receptacle for mail, printing mechanism, means 50 for holding a letter during the printing operation, a swinging top having limited telescoping connection with the upper portion of said receptacle, and means connected with the top for actuating said printing mechanism, 55 for the purpose set forth.
